METHOD OF TREATING LUBRICATING DISTILLATES

Charles Walcott Stratford, Kansas City, Mo., assignor to Stratford Development Corporation, Kansas City, Mo., a corporation of Delaware

Application December 12, 1930
Serial No. 501,758

5 Claims. (Cl. 196—45)

This invention relates to improvements in treating lubricating oil distillates, and refers more particularly to a method for dehydrating the distillate and subsequently subjecting it to treatment with acid and neutralizing agent.

The novelty of the invention lies principally in subjecting distillates to a rapid and intimate contact with acid to eliminate undesirable constituents, with a final treatment with a neutralizing agent such as caustic soda or clay. The acid contacting stages may be with either weak or strong acid and by counterflow of the acid with the oil in the successive stages of treatment. The system contemplates intermediate stages of centrifugal separation between the acid contacting steps. By the treatment, the distillate is first dehydrated in order to eliminate moisture from the oil which is objectionable in the subsequent treating stages. Also an accurate temperature control is maintained over the oil undergoing treatment in order that the distillate shall be supplied to the acid contacting steps at an optimum temperature. The entire method is in a closed system, the oil being passed therethrough continuously, thus affording considerably greater throughput rates than have been possible by the usual batch agitating methods which are at the present time common practice.

The single figure is a diagrammatic view of an apparatus adapted to carry out the process.

Referring to the drawing, 1 and 2 are storage tanks, the former a distillate tank from which is supplied the lube distillate for the system. In the tank 2 is collected treated distillate as it is discharged from the system. The numeral 3 indicates a heat exchanger, 4 is a dehydrator, 5 and 6 are contactors, 7 and 8 centrifuges, 9, 10, 11, 12, and 13 are centrifugal pumps. 14 is a blow case for weak acid, 15 a blow case for strong acid, while 16 and 17 are rate of flow blow cases which may be used with either the weak or strong acid as hereinafter explained.

In operation, the lube distillate is withdrawn from the tank 1 through pipe 18 and is charged by means of the pump 9 through line 19 and heat exchanger 3, thence through pipe 20 to the inlet 21 of the dehydrator 4. A heating or cooling medium is supplied to the exchanger 3 through line 22 and discharged therefrom through pipe 23. Mounted on the top of the dehydrator is a motor 24, driving a shaft 25 upon the lower extremity of which is a circular dispersion plate 26 which is rotated at high velocity by the motor. The liquid distillate, which has been brought to proper temperature in the heat exchanger,

passes from the inlet pipe 21 down the vertical pipe 27 and is discharged upon the upper surface of the rotating plate 26. This plate atomizes the distillate to present a maximum evaporating surface of the infeed oil. In the heat exchanger 3, oil is preferably brought to a temperature ranging from 150° to 300° F. according to the character and nature of the distillate being treated. Different types of oils require different temperatures in order to dehydrate and therefore a range of temperatures must be provided to include lube distillates of different types. The temperature to which the oil is raised in the heat exchanger is dependent not only upon the dehydration, but subsequent desirable temperatures at which the oil is to be treated during the contacting stages. In other words, such temperatures must be maintained as to produce viscosities best adapted to intimate contact with the acid in the subsequent stages, as the viscosity of the oil is one of the determining factors of the contact time and the ease and degree of dispersion which can be produced not only in the evaporator 4 but also in the subsequent contacting and separation stages.

In the upper part of the dehydrator is a flanged connection 27A, to which is hooked up an apparatus for producing a reduced pressure within the evaporator. This apparatus includes a steam vacuum booster pump 28, supplied with steam through a line 29. The discharge of the pump is connected by a pipe 30 with a barometric condenser 31. Cooling water is supplied to the condenser through a line 32 and, on the discharge from the condenser, is a pump 33 which is supplied with steam through the line 34. Discharge from the pump 33 is through a pipe 35, through which the energy steam, air and gas from the barometric condenser are exhausted or brought up to atmospheric pressure. The apparatus shown and described for producing reduced pressure upon the dehydrator is of common type and well known in this particular art.

In the bottom of the dehydrator is accumulated the anhydrous or dehydrated oil, and a liquid level control 36, connected to a valve 37 interposed in a line 20, regulates the infeed of distillate charged to the system. The accumulated anhydrous oil is discharged from the dehydrator through the pump 10, driven by a motor 38. Connected to the discharge pipe 39 of the pump is a recirculation line 40, by means of which the oil of the dehydrator may be circulated back into an infeed connection 41 in order that complete dehydration is assured. A flow indicator 42 and

a valve 43 are interposed in the recirculating line 40, the former indicating the amount of recirculated liquid and the latter furnishing a means for regulating the amount of recirculated distillate.

Distillate discharged from the pump 10 is directed through the line 39, through a meter 44, thence to the contactor 5. A temperature control device 45 is interposed in the line 39 and 10 has a connection with a valve 46 in the steam discharge pipe from the heat exchanger 3. This temperature control on the infeed for the first 15 contacting stage regulates the amount of heat supplied to the incoming distillate in order that it shall be charged to the first contacting stage at an optimum temperature for the acid treatment.

Referring now to the acid supply, as suggested the blow case 14 contains weak acid and the 20 blow case 15 strong acid. Compressed air through the pipe 47 supplies air pressure through connections 48 and 49 to blow cases 14 and 15, respectively and through connection 50 and lines 51 and 52, to blow cases 16 and 17; vents 53 and 54 are connected into lines 51 and 52, and suitable valves are interposed in all of the lines to permit accurate control. Also there is a pressure regulator 55 in the line 47. Weak acid may be 25 discharged from blow case 14 through pipe 56, thence into the rate of flow blow case through connection 57 by the air pressure imposed upon the acid charging system. The rate of flow of the acid may be read upon the gauge glass on blow case 16 as it is discharged through pipe 58. 30 A by-pass 59 is furnished around the blow case. In the pipe 58 which directs the acid from blow case 16 to the contactor 5 is a flow control device 60 regulating the valve 61. The contactors 5 and 6 shown in the drawing are preferably of the type disclosed in my Patent No. 1,736,018.

The acid and oil are intimately mixed in the contactor which constitutes the initial step of acid treating. In place of the weak acid, strong acid may be supplied to this initial contacting stage by withdrawing strong acid from blow case 15 instead of 14 and directing it through pipe 62, thence through cross-over line 63 into blow case 16 and out through the discharge pipe 58 to contactor 5.

From the initial contacting stage 5, whether strong or weak acid is used, the intimate mixture of oil and acid passes out through the line 64 to the centrifuge 7. In this line 64 is a control valve 65 which is regulated by a flow control mechanism 66 in the pipe 39. In other words, the rate of infeed to the contactor is regulated by the discharge valve. In the centrifuge 7 the treated distillate is separated from the acid sludge, the distillate being discharged through the pipe 67 while the acid sludge is drawn off through a line 68 in which is a heat exchanger 69, adapted to facilitate handling thereof. This heat exchanger may be used either for heating or cooling. The distillate discharged through the line 67 is picked up by the pump 11 and forced through the pipe 70 and heat exchanger 71 into the second contactor 6. The heat exchanger 71 may be used either to heat the oil or cool the oil and it is contemplated that the liquid introduced to the contactors may be either heated or cooled prior to introduction thereto in order to produce the optimum temperatures in the subsequent contacting or mixing stages. Either weak or strong acid is supplied to the contactor 6 from blow cases 14 or 15. If weak acid is to be introduced, it is with-

drawn from the blow case through pipe 56, thence through line 63 to line 72 which is a continuation of pipe 62. Through line 72 it can be introduced to blow case 17 through pipe 73, or bypassed around the blow case directly into the contactor. Pipe 74 connects the blow case 17 with the lower end of pipe 72. Above the contactor is flow control mechanism 75 regulating the valve 76 and above each of the contactors are manually operated valves 77 and 78. Strong acid may be supplied to the contactor through line 62 from blow case 15 and thence through the metering blow case 17 or through the by-pass directly to the contactor. The mixed oil and acid is discharged from contactor 6 through line 79 and is introduced to centrifuge 8 where separation is again made; the acid sludge or spent acid is discharged through pipe 80, in which is interposed a heat exchanger 81, thence to the pump 12, which directs the spent acid or acid sludge into the line 82 to be returned to the preceding contacting stage or contactor 5, through pipe 83. Where counterflow operation of the acid and oil is not desired, the acid sludge withdrawn from the centrifuge 8 may be diverted from the system 95 through pipe 84 by manipulation of the valves in lines 82 and 83. The distillate recovered from the second centrifuge 8 is withdrawn through pipe 85 and is picked up by the pump 13 and forced through line 86 through the metering device 87, into a final neutralizing stage 88 where the oil may be given either a treatment with caustic soda or with clay. Where the neutralizing stage is a soda treatment stage, preferably a contactor and separator are used. The separator 100 may be either a centrifuge or a settling device such as is shown in my issued Patent 1,736,018. Where the neutralizing stage is obtained with clay, a contactor and filter are the preferred apparatus. The treated distillate from the neutralizing stage is directed through a line 89 to the 105 distillate storage tank 2.

Valves have been interposed in the lines throughout the system but have been omitted from the explanation in the interest of simplicity. 120 Also it will be noted that by-passing lines are furnished around most of the automatically controlled valves, meters and blow cases to facilitate operation and to prevent shut down in case of faults with the mechanical equipment. It is 125 contemplated also that a cooler may be interposed in the pipe 90 which connects the dehydrator with steam vacuum pump 28. This, however, is optional with the operator and may be eliminated if unnecessary with the particular oil 130 undergoing treatment.

It is contemplated also that in place of the two stages shown, the system may be supplemented with additional stages which shall be connected up in such a manner that weak or strong acid 135 may be supplied in order to obtain a once through operation of either type of acid with the additional contacting stages. These additional stages also should be connected into the system in order that counterflow operation of the acid and oil 140 could be used throughout the system.

As suggested heretofore, different lube distillates have optimum treating temperatures due to variations in viscosity. It will be appreciated that viscosity is a salient consideration in a system of this type in order to produce complete dehydration and to raise the oil to a temperature at which proper treating with acid can be effected in the contacting stages. Control of viscosity is important in order that the oil is satis- 145

factorily treated within the time and power range of the system.

Fundamentally the system is entirely closed in order that it shall not be affected by air and moisture conditions and the oil as it is charged to the acid treating steps is substantially anhydrous, thus eliminating difficulties heretofore encountered with usual methods wherein the moisture in the oil affects acid sludge obtained after acid contacting. A reduced pressure in the evaporator is important to avoid excessive temperature in the subsequent treating stage.

The system contemplates the use of weak or strong acid charged to the separate stages of contacting accompanied by immediate diversion of the sludge from the system from each of the contacting steps. It contemplates also the use of a counterflow operation in which weak or strong acid is charged to the final contacting stage and passed in an opposed direction to the oil in the preceding contacting stages to be finally diverted from the system from the initial contacting stage.

Optional methods for neutralization are suggested and contemplated in the final stage 88. The combination of dehydration and temperature control are important factors in procuring optimum viscosity, a condition of the distillate best adapted for the acid treating steps. The viscosity of the oil is obviously a determining factor on ease and degree of dispersion, both in the dehydrator and in the contacting and separating steps. It is also a factor in the contact which is necessary for satisfactory treatment of the oil.

35 I claim as my invention:

1. A method of treating lubricating distillates comprising the steps of heating the oil, dehydrating it in a stage of reduced pressure, subjecting the oil to acid treatment in a plurality of contacting stages accompanied by intermediate stages of centrifugal separation, followed by a final neutralizing treatment, and regulating the heat supplied to the oil by the temperature of the oil charged to the initial acid treating stage.

45 2. A method of treating lubricating distillates comprising the steps of heating the oil, dehydrating it in a stage of reduced pressure, subjecting the oil to acid treatment in a plurality of contact-

ing stages accompanied by intermediate stages of centrifugal separation, followed by a final neutralizing treatment, and regulating the heat supplied to the oil by the temperature of the oil charged to the initial acid treating stage to produce dehydration, and optimum temperatures and viscosity conditions in the subsequent acid treating stages.

3. A method of treating lubricating distillates comprising the steps of heating the oil, dehydrating it in a stage of reduced pressure, subjecting the oil to acid treatment in a plurality of contacting stages accompanied by intermediate stages of centrifugal separation, followed by a final neutralizing treatment, and regulating the heat supplied to the oil by the temperature of the oil charged to the initial acid treating stage, creating a local cyclic movement of the oil through the dehydrating stage to effect complete dehydration of the oil and permit accurate and constant metering of the oil charged to the subsequent acid treating stages.

4. A method of treating lubricating distillates comprising the steps of heating the oil, dehydrating it in a stage of reduced pressure wherein the oil is dispersed to offer increased evaporating surface, subjecting the oil to acid treatment in a plurality of contacting stages accompanied by intermediate stages of centrifugal separation wherein the oil is passed in counterflow relation to the acid, followed by a final neutralizing treatment, regulating the heat supplied to the oil by the temperature of the oil charged to the initial acid treating stage.

5. A method of treating lubricating distillates comprising the steps of heating the oil, dehydrating it in a stage of reduced pressure wherein the oil is dispersed to offer increased evaporating surface, subjecting the oil to an acid treatment in a plurality of contacting stages accompanied by intermediate stages of centrifugal separation, utilizing acids of different concentration in the respective contacting stages, subjecting the oil to a final neutralizing treatment, regulating the heat supplied to the oil by the temperature of the oil charged to the initial acid treatment stage.
